UNITED STATES PATENT OFFICE.

LUDWIG W. NORBERG, OF BUFFALO, NEW YORK.

STAIRWAY CONSTRUCTION.

Application filed July 3, 1926. Serial No. 120,435.

This invention relates to a stair construction and more particularly to metal stairways such as are used in factories, public buildings, etc.

- 5 One of the objects of this invention is to provide such a stairway which is strong and durable, and is easily and quickly assembled without requiring the use of special skill or tools.
- 10 A further object is to provide such a stairway construction in which the parts, of which the stair is composed, adapt themselves to their proper positions relative to each other, and in which the parts can have a considerable margin of inaccuracy without impairing the strength or appearance of the stairs.

A still further object is to provide such a stair construction which can be manufactured, and erected at low cost.

In the accompanying drawings:

Figure 1 is a horizontal sectional view of the preferred construction of my stairway, the same being taken on line 1—1, Fig. 2. Figure 2 is a vertical longitudinal section taken on line 2—2, Fig. 1. Figure 3 is a vertical transverse section of the same taken on line 3—3, Fig. 2. Figure 4 is an enlarged longitudinal section showing one of the arcuate fastening bolts. Figure 5 is an enlarged transverse section of the same taken on line 5—5, Fig. 4. Figure 6 is an enlarged fragmentary longitudinal section showing the preferred form of nosing. Figure 7 is a view similar to Fig. 1, and showing a modified form of my invention, the cement filler being removed. Figure 8 is a vertical longitudinal section of the modified form of stair construction shown in Fig. 7. Figure 9 is a vertical transverse section taken on line 9—9, Fig. 8. Figure 10 is an enlarged fragmentary longitudinal section showing one of the curved fastenings used with a short section of an abutment bar. Figure 11 is a section on line 11—11, Fig. 10. Figure 12 is a fragmentary longitudinal section of a form of nosing employed in connection with the modified form of my invention. Figure 13 is a similar sectional view showing another form of nosing and tread. Figure 14 shows the manner in which my invention may be used in connection with an all metal stairway.

Similar reference numerals refer to similar parts in each of the several views.

Referring to the preferred form of my in-

vention shown in Figs. 1—6, the steps or stairs are supported by the usual inclined stringers 14, which are made of metal and are supported at their upper and lower ends in any well known and approved manner. These stringers are preferably rectangular in cross section presenting opposing flat faces, between which the steps or stairs are arranged. Each of the steps comprises a riser 15 and a tread 16, which are formed integrally and are disposed at right angles to each other, and abut at their opposite ends against the inner flat faces of the stringers 14. The means for securing each step to the stringer comprise a plurality of hook bolts 17 which connect each tread 16 with the stringers. Each of these bolts is curved or arcuate and preferably two of such bolts extend through the stringer below one end of each tread, and pass upwardly through the tread. These bolts may be threaded at both ends and provided with nuts, or the same may be provided with heads, which may be countersunk into the stringer, as shown at the left of Fig. 3 so as to provide a smooth surface on the outer side thereof. The treads are supported by a plurality of quarter round bearing bars 18, each of which extends longitudinally of the stairway and is confined between the hook bolts, tread and stringers, the flat faces thereof engaging the under side of the tread and the inner face of the stringer, and the round face thereof engaging the inner sides of the arcuate hook bolts.

It is obvious that after the parts of the stairway are loosely assembled, the hook bolts may be drawn tight, which forces the tread down upon the quarter round bearing bar 18 and thereby securely fastens the ends of each tread to the stringers. The tread is also supported throughout its entire width by the bearing bar, and is therefore very rigid. This arrangement of hook bolts in combination with the bearing bar also serves to render the parts self aligning, since the holes in the stringer which receive the bolts are formed in the stringer at the factory, and it is therefore only necessary to assemble the parts loosely and draw the hook bolts tight when the stairway is being erected.

To guide the treads and risers into proper position with relation to the spacing of the steps, and also to solidly interlock the outer corners of each riser and tread without using bolts or other fastenings for this purpose, a nosing 19 is provided on the upper end of

the riser 15, which extends over and around a reversely formed hook portion 20 on the front end of the tread. The nosing is composed of a base portion 21 extending obliquely upwardly and forwardly from the body of the riser, a horizontal tread portion 22 extending rearwardly from the upper end of the oblique portion, and a depending lip 23 arranged at the rear end of said tread portion. The hook portion of the tread is composed of an oblique portion 24 extending upwardly and forwardly from the front end of the tread, and having an inclination corresponding to the inclined base portion 21 of the nosing, and an upper flange 25 extending obliquely upwardly and rearwardly from the upper end thereof. This flange is of such a length as to firmly engage the inner side of the rear portion of the nosing and is preferably sufficiently yielding to adapt itself to the nosing as the successive steps are assembled. In assembling the stairway, assuming the stairway to be built from the top down, the step to be fastened in place is elevated and its nosing locked under the flange 25 of the next higher step which has previously been secured. The step is then swung down, the nosing interlocks with the reversely formed portion of the fixed tread, and the same may then be bolted in place. The inclined engagement between the nosing and the tread permits the same to be moved up and down to adapt the step to inaccuracies, and after it is in position holds the same until bolted. The tread is then filled with cement 26, which is poured so as to be flush with the tread 22 of the nosing and extends to the riser at the rear end of the tread. After the cement hardens, the nosing is, of course, embedded and rendered solid.

In the modified form of my invention shown in Figs. 9-13 the arcuate body portions of the hook bolts 17 are arranged above the tread and are embedded within the cement. In this construction one hook bolt is arranged at the center of the tread 16 at each end thereof; one extends through the lower end of the riser, and one is arranged at each end of the nosing, which last mentioned bolt penetrates both the upper end of the riser and the front end of the tread. This form permits the stairs to be moved a considerable extent both vertically and horizontally by tightening the several bolts to a greater or less extent, and therefore enables the stairway to be readily adjusted and properly assembled without cutting or re-drilling inaccurately made parts. In this construction short sections of quarter round bars 27 may also be placed under the hook bolts 17, the function of the bars being to serve as an abutment and guide for the step and bolts, the upward movement of the tread, and the lateral movement of the riser

being limited thereby when the bolts are drawn tight.

Inasmuch as in this form the parts of the tread and riser forming the nosing of the step are bolted together, the interlocking nosing shown as the preferred construction need not be employed, but any well known and approved form of nosing construction may be used. As shown in Figs. 7, 8, 9 and 12, the riser may be flat and the tread formed to provide a vertical flange 28 at its front end, the hook bolt being headed to give the nosing a finished appearance, or as shown in Fig. 13, the head of the bolt may be countersunk, and the step provided with a tread plate 29 cemented to the upper side of the tread and having a nosing 30 overhanging the nosing of the step.

This invention, as shown in Fig. 14 may also be used in connection with an all steel stairway, the hook bolt 17 extending upwardly through a checkered tread 31 and having a round head at its upper end. The nosing 32 in this construction preferably overlaps the upper end of the riser and is secured thereto by a bolt 33 passing therethrough.

As a whole, this invention provides a very simple, inexpensive, and easily assembled stair. The stairway is also very strong and rigid and of attractive appearance.

I claim as my invention:

1. In a stairway, a stringer, a step extending laterally outward from said stringer, said step comprising a riser section and tread section, a cement filler arranged on the upper side of said tread section, and means for fastening said tread to said stringer comprising hook bolts arranged above said tread and embedded in said cement, the ends of said hook bolts extending through said stringer and said tread.

2. In a stairway, a stringer, a stair member projecting perpendicularly outward from said stringer, said stair member being provided at a point spaced from said stringer with a hole, and said stringer being provided at a point spaced from said stair member with a hole, and means for fastening said stair member to said stringer comprising a threaded hook bolt penetrating said holes and a nut arranged on said hook bolt and adapted to draw said stair member toward said stringer.

3. In a stairway, a stringer, a stair member projecting perpendicularly outward from said stringer, said stair member being provided at a point spaced from said stringer with a hole, and said stringer being provided with a corresponding hole spaced a substantially equal distance from said stair member, and means for fastening said stair member to said stringer comprising an arcuate hook bolt disposed perpendicularly to said stair member and stringer and passing

through said holes, and a nut on said hook bolt adapted to draw said stair member toward said stringer.

4. In a stairway, a stringer, a stair member projecting perpendicularly outward from said stringer, said stair member being provided at a point spaced from said stringer with a hole and said stringer being provided at a point spaced from said stair member with another hole, and means for fastening said stair member to said stringer comprising an arcuate hook member penetrating said holes, an integrally formed head at one end of said hook bolt and a nut at the other end of said arcuate hook bolt and adapted to draw said stair member toward said stringer.
5. In a stairway, a stringer, a stair member projecting perpendicularly outward from said stringer, said stair member being provided at a point spaced from said stringer with a hole and said stringer being provided at a point spaced from said stair member with a second hole, both of said holes being substantially equidistant from the point of juncture of said stair member and stringer, and means for securing said stair member

to said stringer comprising an arcuate hook bolt penetrating said holes, a nut arranged on said hook bolt and adapted to draw said stair member toward said stringer, and an abutment confined between said hook bolt, stringer and stair member.

6. In a stairway, a stringer, a stair member projecting perpendicularly outward from said stringer, said stair member being provided at a point spaced from said stringer with a hole and said stringer being provided at a point spaced from said stair member with a second hole, both of said holes being substantially equidistant from the point of juncture of said stair member and stringer, and means for securing said stair member to said stringer comprising an arcuate hook bolt penetrating said holes, a nut arranged on said hook bolt and adapted to draw said stair member toward said stringer, and a quarter round bar arranged between said stringer, stair member and arcuate hook bolt.

In testimony whereof I hereby affix my signature.

LUDWIG W. NORBERG.
